ATTORNEY

UNITED STATES PATENT OFFICE.

GEORGE F. McCARTY, OF SAN JOSE, CALIFORNIA.

ROUTING TOOL.

Application filed July 25, 1921. Serial No. 487,372.

To all whom it may concern:

Be it known that I, GEORGE F. McCARTY, a citizen of the United States, and a resident of San Jose, in the county of Santa Clara 5 and State of California, have invented certain new and useful Improvements in Routing Tools, of which the following is a specification.

My invention relates to a type of routing 10 tool particularly for use in setting hinges and similar devices which require a recessed bed.

In routing out the edge of a door or case- 15 ment window preparatory to mounting a hinge thereon, it is difficult to form a bed of uniform depth and width because of the 20 uncertain and varying characteristics of the wood being worked. It is the object of the present invention to provide a device whereby a recess of uniform depth and width may 25 be quickly formed in wood of any character.

It is a further object to provide a device of the character indicated that can be adjusted for varying widths of recesses and that is 30 also adjustable for varying depths of re- cesses.

In the drawing:—

Figure 1 is a side elevation of the device in an operative position, part broken away.

Figure 2 is a plan view of the same. 35 Figure 3 is an enlarged elevation of the cutter blade.

Referring more particularly to the drawing 40 1 indicates a flat bar mounted on handle 2 and provided with a slot lengthwise there- of as at 3. At 4 I show a blade supporting member provided with a slot 5, a bolt 6 carrying a wing nut 7 passing through slots 3 and 5 whereby the bar and supporting member may be adjusted longitudinally as 45 desired.

Supporting member 4 is provided with spaced pairs of ears as 8—8 and 9—9 on one edge thereof as shown to properly place the member on bar 1 and to serve as supports for 50 the cutting blade. Extending upwardly on member 4 in an opposite direction to ears 8 and 9 and arranged between each pair of ears, is a supporting element as 10 and 11 respectively, each element having a vertically arranged slot formed therein as at 12 55 and 13.

At 14 is shown a blade having a slot 15 formed therein, and at 16 is a bolt engaging slots 12 and 13 and securely locking the said 55 blade in position on element 10. Blade 14

fits snugly between ears 8—8 and has an outwardly and rearwardly extending cutting edge 17.

In its practical application the head 18 of bolt 6 operates as a gauge, the said bolt being 60 moved backward or forward until the space between it and the cutting edge 17 of the knife is the same as the required width of the recess, whereupon, the wing nut 7 is 65 tightened. The depth of the cut is now determined by raising or lowering blade 14 and tightening up bolt 16.

The device being properly set for the work to be done, the cutting edge 17 is applied to the edge of the work 19 at 20 and forced in- 70 wardly along line 21. The first cut having been made a second cut is made along line 22 and the narrow strip between the two 75 cuts removed. Since the grain of the wood in a door or window runs parallel with its longer edge the cuts are across the grain and the narrow strip thus cut is readily removed. The first cuts having been made successive 80 cuts are made as indicated by the parallel dotted lines 23 and the several strips re- 85 moved. When a sufficient number of the strips have been cut out it will be found that a recess of perfectly uniform depth and width has been formed, only requiring a slight smoothing at the edge 24 to prepare it 90 for receiving a hinge leaf. The roughness at edge 24 is due of course to the fact that the cutting is across the grain of the wood and the short pieces between the successive cuts are merely broken away. The bar 1 should, 95 of course, be wide and long enough to provide a solid bearing surface on the work.

The blade supporting member 4 is here 100 shown with duplicate blade holding elements 10 so that the same may be reversed on bar 1. As shown in solid lines the device is arranged for a left-handed workman. For a right-handed workman the member 4 is arranged as shown in dotted lines at 25, in which case a right-handed blade must be used as at 26.

It may be seen from the foregoing that the device disclosed will quickly and accurately do the work required; it is adjustable for any depth and width of recess; it is readily 105 adapted for use for a right or left-handed workman.

It is to be understood of course, that while I have herein shown and described one particular embodiment of my invention, changes 110

in form, construction and method of operation may be made within the scope of the appended claim.

I claim:—

- 5 A routing tool comprising a bar having a slot formed therein longitudinally thereof, a blade holder having a slot formed therein longitudinally thereof, means for engaging

both of said slots and locking said bar and holder together, spaced pairs of ears formed on said holder to engage one edge of said bar, a blade supporting means upstanding on said holder between each pair of ears, and a vertically adjustable blade arranged on each blade supporting means.

GEORGE F. McCARTY.
